ARTHUR E. RICE, OF BIGLERVILLE, PENNSYLVANIA, ASSIGNOR TO RICE, TREW & RICE CO. INC., OF BIGLERVILLE, PENNSYLVANIA, A CORPORATION OF PENNSYLVANIA

PACKING LINER

Original application filed March 20, 1931, Serial No. 524,159. Divided and this application filed December 15, 1931. Serial No. 581,177.

This application is a division of my pending application Serial No. 524,159, filed March 20, 1931.

- This invention relates to a packing liner 5 for use in packing fruit and the like, and it is primarily an object of the invention to provide flexible means coacting with portions of the liner to hold the same together, the liner when removed being so constructed as 10 to permit expansion of the liner while the flexible means is capable of being removed from the liner when the liner is filled and an inverted container is positioned over the filled liner.
- 15 The invention consists in the details of construction and in the combination and arrangement of the several parts of my improved packing liner whereby certain important advantages are attained and the device 20 rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawing, wherein:—

- 30 Figure 1 is a sectional view illustrating an initial step of the method as herein disclosed;

Figure 2 is a sectional view illustrating a succeeding step;

- 35 Figure 3 is a view partly in section and partly in elevation illustrating the assembly of the various parts before the removal of the holding member from the liner;

- Figure 4 is a fragmentary view in elevation 40 illustrating the holding member as herein employed in applied position with respect to the liner;

- Figure 5 is an enlarged transverse-sectional view taken through the holding member as 45 herein disclosed.

- As disclosed in the accompanying drawing, 50 F denotes a facing form upon which a facing layer of fruit or the like is adapted to be arranged whereupon a tub T with an applied liner L are placed upon the form. The

assembled tub T and liner L are then properly filled with fruit or the like and after the tub T has been removed a basket B or other desired container in an inverted position is placed over the liner L and its content.

55 The liner L comprises a sheet of paper stock or other suitable material with preferably the grain of such stock disposed in a general direction lengthwise of the liner to afford a strong wall not liable to breakage or 60 yield and which also gives to the liner a natural tendency to readily open or spread out, thus facilitating the application of the liner in working position.

The liner L is initially of a split form or 65 loose end type and in its opposite end portions is provided with the openings 1 so positioned that when the end portions of the liner are in overlapping relation the openings 1 at one end portion will register with the corresponding 70 openings 1 at the other end portion of the liner to permit the threading through said registering openings of an elongated member or key M.

As herein disclosed, the member M is of 75 a length to extend beyond an open end of the connected liner and this member M possesses sufficient flexibility to allow the same to be readily withdrawn or removed bodily as a unit upon endwise movement when the inverted basket or container B is applied over the liner L and its content. Upon removal of this member or key M, the end portions of the liner L will be entirely disconnected thus permitting the liner L to expand, or more 80 particularly to allow sufficient slippage of the overlapping end portions of the liner L, so that the liner content under its own weight

85 will settle to compensate itself to any irregularities which may be present in the surrounding wall of the basket or container B while at the same time the facing layer upon the form F is maintained immovable. When the basket or container B with its content is upended, the content of the basket or 90 container B is in proper placement therein and the facing layer of fruit or the like maintaining without disturbance substantially its original formation upon the facing form F.

95 The member or key M may be of any mate- 100

rial or materials possessing sufficient flexibility to allow the same to be readily withdrawn while the inverted basket or container B is applied over the liner L and its content but, as herein disclosed, the member M comprises two superimposed layers or laminations *a* of paper stock having interposed therebetween a lamination *b* of asphaltum. It has been found in practice that a member or key M constructed in this manner possesses sufficient strength to hold the overlapping portions of the liner L yet readily flexes without breaking as the member or key M is withdrawn downwardly from its applied or working position.

The member or key M is threaded through the openings 1 of the overlapping portions of the liner L before said liner L is applied within the tub T with the extended portion of the member M disposed beyond the larger end of the tub T, as illustrated in the accompanying drawing. This extended portion of the member M is then bent over and outwardly with respect to the adjacent end edge of the tub T by the operator so that when the inverted basket or container B is placed over the filled liner L, this bent portion of the member M will be properly disposed beyond the periphery of the adjacent portion of the basket or container B so that it may be readily grasped by the operator for withdrawing the member M before the basket or container B and its content is upended.

With this method of packing as hereinbefore set forth, the liner L within the basket or container is so maintained therein as to effectively protect the facing layer of fruit or the like and more especially when the lid or cover is applied to the basket or container. This is due to the fact that the liner when applied within the basket or container will at all times have a portion thereof extended beyond the open face of the basket or container because before the basket or container is upended the content of the basket or container has firm settlement within the basket or container.

From the foregoing description it is thought to be obvious that a packing liner constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:

1. A holding key for a basket liner having registering openings in overlapping portions,

said key comprising a bar bendable at any point intermediate its ends to substantially a right angle position, said bar initially having sufficient rigidity to maintain the overlapping portions of the liner in engaged position, said key being of a length when applied to a liner to extend a substantial distance beyond an end of the liner. 70

2. A holding key for a basket liner having registering openings in overlapping portions, 75 said key comprising a bar bendable at any point intermediate its ends to substantially a right angle position, said bar initially having sufficient rigidity to maintain the overlapping portions of the liner in engaged position, said key being of a length when applied to a liner to extend a substantial distance beyond an end of the liner, said key comprising superimposed laminations of paper stock, and adhesive means for connecting the laminations. 80

3. A holding key for a basket liner having registering openings in overlapping portions, 85 said key comprising a bar bendable at any point intermediate its ends to substantially a right angle position, said bar initially having sufficient rigidity to maintain the overlapping portions of the liner in engaged position, said key being of a length when applied to a liner to extend a substantial distance beyond an end of the liner, said key comprising superimposed laminations of paper stock and a lamination of asphaltum interposed between the first named laminations for adhesively connecting said first named laminations without interfering with the bending of the key. 90

4. In combination with a packing liner for use in packing fruit and the like having overlapping portions, a holding key for the liner 100 insertible at a plurality of points through the lapping portions of the liner, said key comprising a bar bendable at any point intermediate its ends to substantially a right angle position, said bar having sufficient rigidity to 105 maintain the lapping portions of the liner in engaged position, said key being of a length to extend beyond an end of the liner. 110

In testimony whereof I hereunto affix my 115 signature.

ARTHUR E. RICE.
